(57) **CLAIM**

The ornamental design for a flexible printed circuit board for a phototherapy cap, as shown and described.

DESCRIPTION

FIG. 1 is an upper perspective view of a flexible printed circuit board for a phototherapy cap in a first configuration showing our new design;

FIG. 2 is a lower perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof;

FIG. 8 is a bottom plan view thereof

FIG. 9 is an upper perspective view of the flexible printed circuit board for a phototherapy cap in a second configuration;

FIG. 10 is a top plan view thereof;

FIG. 11 is a bottom plan view thereof; and,

FIG. 12 is a left side elevational view thereof, the right side elevational view being a mirror image.

The right side elevation view of the flexible printed circuit board for a phototherapy cap according to FIGS. 1 to 12 in the second, flat position is a mirror image of the left side elevation view of FIG. 12.

The broken lines immediately adjacent the shaded areas represent the bounds of the claim, while all other broken
